STORAGE CONTAINER FOR ARTIST'S MATERIALS OR THE LIKE

Andrea Alston Day, 1040 Iliff St., Pacific Palisades, Calif., and Alec von Drachenfels, 1342 Castro St., Monterey, Calif.

Filed Nov. 22, 1971, Ser. No. 201,246

Term of patent 14 years

Int. Cl. D19—06
U.S. Cl. D87—1 R

FIG. 4

FIG. 1.

FIG. 2.

FIG. 3.

FIG. 1 is a perspective view of a storage container for artist's materials or the like, in open position showing our new design;

FIG. 2 is a front elevational view thereof with the front lid in open position and the top cover closed;

FIG. 3 is a side elevational view thereof with both the front lid and top cover closed; and

FIG. 4 is a fragmentary plan view thereof with both the front lid and top cover open.

We claim:

The ornamental design for a storage container for artist's materials or the like, substantially as shown and described.
